UNITED STATES PATENT OFFICE.

AUGUST CARL HUMMEL, OF CINCINNATI, OHIO, ASSIGNOR TO A. KIMBALL CO., OF NEW YORK, N. Y., A COMPANY OF NEW YORK.

TAG FOR TEXTILE FABRICS.

Application filed June 1, 1921. Serial No. 474,132.

To all whom it may concern:

Be it known that I, AUGUST CARL HUMMEL, a citizen of the United States, residing at Cincinnati, in the county of Hamilton 5 and State of Ohio, have invented certain new and useful Improvements in Tags for Textile Fabrics, of which the following is a specification.

This invention relates to tags used in labeling textile goods and fabrics and has particular reference to the structural features by which it may be attached to the goods or fabric. As is well known, tickets or tags, usually made of paper, comparatively thin cardboard, or other analogous material having a surface containing printed or written data, are placed on textile goods and fabrics to be sold, and various means have been employed heretofore for holding such tags or tickets in place. The fastening means has usually been something separate and distinct from the tag or ticket itself, such as glue or paste, or string or stitching or small wire staples passing through the tag and fabric, but each of these has some objectionable characteristic such as injuring the fabric or difficulty in applying and removing the tag. Where the attempt has been made to dispense with such separate means for fastening and to include the fastening means as a part of or attached to the tag or ticket in such way as to avoid punctures in the fabric, it has heretofore been found necessary to use an excessive amount of material in the tag and to add structural features which involve prohibitive cost compared to the advantages over other known means, and the results have not been satisfactory for additional reasons. According to the present invention, a complete tag with its fastening means may be cut at one operation of a properly shaped cutting die from a sheet of material such as cardboard of the proper thickness of the exact size desired, with no waste of material, thus insuring the utmost ease and economy in manufacture. The tag so cut may be securely attached to the fabric on one face slightly removed from the margin by simple hand manipulation without puncturing the fabric or injuring it in any way beyond causing some lines of fold. The tag may also be removed easily without the slightest danger of injuring the fabric. The novel features will be more

fully understood from the following description and claims taken with the drawings. 55

In the drawings: 60
Figure 1 is a front view of a complete tag with its detachable tab embodying the invention.

Figure 2 is a similar view showing the tag applied to the face of a piece of textile fabric and secured thereto through the cooperative action of the tag, the tab, and the fabric, and 65

Figure 3 is an enlarged section on the line 3—3 of Figure 2; and

Figure 4 is a front view of a tag embodying the invention showing a modified form 70 of slot in the tag.

In the particular embodiment of the invention shown, for purposes of illustration the main body 10 of the tag is rectangular in form with rounded corners for neatness, 75 and centrally at the top there is a tab extension 11, circular in form, and integrally connected to the main body at its facing edge by the narrow and short strip 12. The main body 10, tab 11, and connecting strip 80 12, are cut from a single flat sheet of material of such stiffness and thickness as to maintain its shape under the usual conditions of use, and I prefer for this purpose comparatively thin card board of the type 85 generally used in tags, although the invention is of course not limited to the use of any particular material so long as it has the characteristics desired. Within the margin 90 of the main body 10 an opening 13 is formed, and it is preferably in the shape of a vertical slot centrally arranged below the tab 11, and is preferably slightly longer than the diameter of tab 11. This slot or opening however is of such width that a folded section of the fabric to which it is to be applied may be pulled through it and also such that when tab 11 is removed from the main body 10 by breaking the connecting strip 12 and placed flat over said slot 100 the tab will overlap the side edges substantially throughout its length from one end to the other. The outlined rectangular space 14 below slot 13 is adapted to receive any written or printed data or information 105 which the card is to carry.

In applying the tag to a piece of textile fabric the tab or disk 11 is torn or pulled

loose from the main body 10, breaking the connecting strip 12, and this tab is then inserted beneath the fabric edgewise to form a small fold, and the fabric and tab or disk 5 thrust through the slot, after which the tag is turned parallel to the main body 10. This may be accomplished by pulling one margin of the folded fabric immediately adjacent the slot on the side from which the folded 10 fabric originally passed through the slot in the reverse direction which will twist the disk around to parallel position where it will serve as a clasp somewhat similarly to the button of a garter when it is thrust along 15 with the fabric to the narrow part of the clasp. Thus the fabric encloses the tab in a pocket 16 consisting as shown in Figure 3 of continuous fabric passing through slot 13 and up over the tab at all points around its 20 margin. A pull on the fabric around the opening on the side opposite to the tab will make the pocket fit tight on it and hold it close against the main body 10 and give a neat appearance. The tag 10 may be made 25 to occupy a position at the desired distance from the edge of the fabric by pulling the fabric up while holding the tag, so that the material will frictionally move in through the opening over the tab and out through 30 the opening, whereupon the tag or fabric may be thrust out of the slot again.

While this change in the position of the tag may be brought about by deliberate intent and by the use of sufficient force, it cannot occur accidentally through any conditions to which such fabric is ordinarily subjected, but on the contrary the tag will remain permanently where applied.

In use if desired, a strip of paper 17, 40 shown in dotted lines in Figure 2, may be pasted to the main body 10 and extend over the pocket 16 of fabric containing the tab or key 11, to prevent or detect tampering with the tag, and it may have on it any printed 45 notice or warning desired.

Furthermore the principle of my invention is obviously open to endless modification. Thus in Figure 4 I have shown a form 50 of slot which has wide ends as at 20, and a mere slit or knife cut as at 21 between the ends. The locking feature, by means of the strip 17, takes the place of expensive sealed tags of the present time and absolutely prevents removal of the tag without exposure 55 to detection, as in wearing a garment and then returning it to the seller.

As is evident, the disks could be furnished separately from the tags and made 60 of any desired material and shape and while I have shown two specific embodiments of my invention, it is of course understood that my invention is not limited to the particular form of the parts shown beyond what the terms of the claims require.

Having thus described my invention, what

is claimed as new and desired to be secured by Letters Patent is:

1. A tag for labeling textile goods and fabrics comprising a main body consisting of a flat card having a slot therethrough 70 with closed ends, and a tab constituting an integral extension from said card at one edge, the connection being narrow and easily breakable and the tab being of such size and shape as to fit over the slot opening substantially from one end to the other. 75

2. A tag for labeling textile goods and fabrics comprising a flat main body portion of cardboard having therein a slot with closed ends near one edge and a circular tab 80 extension from one edge integrally connected therewith by a narrow strip and of such size as to fit over said slot between its ends.

3. A tag for labeling textile goods and fabrics comprising a flat main body portion of cardboard having therein a slot with closed ends, and a tab of cardboard detachably secured to the main body portion and of such size and shape as to fit over the slot 85 overlapping its side edges. 90

4. A tag for labeling textile goods and fabrics comprising a body portion adapted to bear identifying marks, said body portion having an enclosed slot therein, and a disk-like locking button sufficiently thin to pass readily edgewise through the slot and of sufficient area to overlap the walls of the slot when turned parallel with the body portion. 95

5. A tag for labeling textile goods and fabrics comprising a body portion adapted 100 to bear identifying marks, said body portion having an enclosed slot therein, and a disk or the like adapted to pass edgewise but not frontally through the slot, said disk comprising an integral part of the body connected thereto by a frangible neck. 105

6. The combination with a piece of textile fabric of a labeling tag thereon composed of cardboard having therein a slot closed at its 110 ends through which a continuous pocket of said fabric extends from one side, and a button like disk in said pocket fitting it closely and lying parallel with, close to and entirely at the other side of said tag at said slot locking the tag on the fabric. 115

7. The combination with a piece of textile fabric of a labeling tag thereon composed of cardboard having therein a slot closed at its ends through which a continuous pocket of said fabric extends from one side, and a button like disk in said pocket fitting it closely and lying parallel and close to said tag at said slot locking the tag on the fabric, a sealing strip secured to the body of said tag on opposite sides of said disk containing pocket and extending across it in close contact with it. 120

8. The combination with a piece of textile fabric of a labeling tag thereon having an 125

5 enclosed slot therein through which a complete fold of the fabric a material distance from its margin extends in pocket like form and a disk or the like having a width and length materially greater than the width of said slot held tightly in and substantially enclosed by said pocket like fold close along and across said slot entirely on the side of said tag opposite to that on which the main

10 body of the fabric is.

9. A tag for labeling textile goods and fabrics, comprising a flat body of cardboard having an opening therein and a flat locking tab of the same material so proportioned 15 in size and shape to the size and shape of the opening that, when the fabric is passed through the opening and drawn over the tab with the tab lying parallel with and above the face of the body and covered by the fab-

20 ric, the fabric and tab are held against withdrawal down through the opening.

10. A tag for labeling textile goods and fabrics comprising a flat main body portion and an integral tab portion of cardboard, the said body portion having therein an 25 opening of a size and shape so related to the size and shape of the tab portion that, when the fabric is passed through the opening and drawn over the tab with the tab lying parallel with and above the face of the body 30 and covered by the fabric, the fabric and tab are held against withdrawal down through the opening.

11. A tag for labeling textile goods and fabrics comprising the construction defined 35 in claim 10 in which the tab portion is connected to the body portion by a narrow easily breakable connection.

In testimony whereof I affix my signature.

AUGUST CARL HUMMEL.
